HAIR CURLER

Edith Ratner and Alfredo Pastore, Brooklyn,
N. Y.; said Ratner assignor to said Pastore

Application March 10, 1950, Serial No. 148,992

5 Claims. (Cl. 132—37)

1

The present invention relates to hair curlers of the well known type, commonly called curling irons, in which the hairs of a lock to be curled are wound around and held in snug contact with a heated element in the form of a rod or tube. Such hair curlers are sometimes referred to as curling tongs because they include a lever pivotally connected to the heated element and biased for movement into engagement with the latter. In use, the free ends of the hairs in the lock to be curled are clamped between the heated and clamping elements after which those elements are rotated about their own axis so that each hair is wound to form one or more convolutions. In the use of such a hair curler, the hair wound around the heated and clamping elements, is subjected to a heating action for the brief period, usually a few seconds only, required to give the convolutions a definite tendency to retain their general ring shapes when the convolutions are loosened and separated from the curling iron.

The general object of the present invention is to provide a hair curler of the type specified which is a self contained unit including a fuel burning heater element, and which is inherently simple in construction and inexpensive to construct, and is small enough to be readily carried in a lady's handbag or coat pocket.

A further object of the invention is to provide the hair curler of the character specified in which the heater element is of the cigarette lighter type, and in practice the heater element included in our novel hair curler unit may well be a cigarette lighter of a commercially available type.

The various features of novelty which characterize our invention are pointed out with particularity in the claims annexed to and forming a part of this specification. For a better understanding of the invention, however, its advantages, and specific objects attained with its use, reference should be had to the accompanying drawing and descriptive matter in which we have illustrated and described preferred embodiments of the invention.

Of the drawings:

Fig. 1 is an elevation partly broken away and in section;

Figs. 2, 3, and 4 are perspective views each illustrating a different element of the hair curler;

Fig. 5 is a partial section on the line 5—5 of Fig. 1;

Fig. 6 is a section on the line 6—6 of Fig. 1; and

Fig. 7 illustrates a modified curler element. In the preferred form illustrated, our novel

hair curler comprises three separable metallic elements A, B and C preferably formed wholly or mainly of thin metal. The element A is a cigarette lighter, advantageously of a commercially available type comprising a hollow cylindrical body 1 enclosing a wick and fuel chamber, and having a central uprising wick tube at its upper end and a closure 3 at its lower end, removable to permit said chamber to be charged with a suitable liquid combustible, or fluid fuel. The body 1 is formed with a longitudinal rib 4 extending radially away from one side of the body and supporting a flint tube 5 at its free edge. The upper end of the tube 5 is open to permit the protrusion of the upper end portion of a flint 6 which has its body portion within the tube 5. The flint tube is provided at its lower end with a closure 7 removable for the insertion of flint. Customarily the flint tube encloses a helical compression spring acting between the closure 7 and the flint in the tube.

The protruding end of the flint 6 engages the periphery of an ignition disc 8. The latter is mounted for rotation on a pivot 9 having its ends supported in ears or end extensions 10 of a perforated flange 11. The body portion of the flange 11 is in the form of a cylinder segment extending through an arc of 300° or so around the axis of the cylinder 1, and having its lower edge integrally connected to the upper end of the cylinder 1. The disc 8 has its peripheral edge serrated and is so located relative to the wick tube 2 that when the disc 8 is rotated in a counterclockwise direction as seen in Figure 1, the sparks formed pass into contact with the portion of the wick protruding through the wick tube 2 and into the path of fuel vapor escaping from the fuel chamber through the tube. The upper edge of the flange 11 is at a level appreciably above the upper end of the wick tube, and forms an ignition space wall into which air can pass through the flange perforations.

Except when fuel is being burned to heat the curling iron, the upper end of the tube 2 is effectively closed by a cup-like closure element 12. The latter is carried by arms 13 which straddle the disc 8 and are mounted on the pivot 9. Customarily, the closure element 12 is spring biased for movement into its closing position and is so associated with the disc 8 that as the finger of the user turns the closure device 12 counterclockwise into its open position shown in Fig. 1, the disc 8 is simultaneously rotated to create sparks and thereby ignite the fuel passing away from the upper end of the tube 2. Customarily,

there is a wheel and ratchet connection between the closure 12 and the disc 8, which causes the disc 8 to turn counter-clockwise with the closure member 12 as the latter is turned out of its closed position, and allows the disc 8 to remain stationary while the closure is being returned to its closed position. Further references to the construction and operation of the ignition and extinguishing features of the element A are unnecessary as those features are not claimed as novel herein, but on the contrary, may be of well known construction. For the purposes of the present invention however, the particular form of the cigarette lighter element A illustrated, is especially desirable because its lateral rib 4 and its perforated upper end extension 11 facilitates its attachment to and separation from the elements B and C of our novel hair curler.

The unit B comprises a heater element 20 in the form of an open ended tube coaxial with the body 1 of the element A, and above and spaced away from the upper end of the wick tube 2 as is shown in Fig. 1. The tubular heater element 20 is of a diameter substantially smaller than the body 1 and has its lower end integrally connected through a flange 21 to a slotted cylinder 22 adapted to surround and form a frictional connection with the curved portion of the flange 11. The rate at which heat is transferred to tube 20 from the hot gases passing into the lower end of the tube from combustion space surrounded by the slotted cylinder 22 may be substantially increased by a copper wire helix 25 in the tube 20 and in snug engagement with the inner wall of the latter.

As shown the cylinder 22 is formed with a plurality of narrow elongated slots 23 parallel to the axis of the element B, and to a substantial wider slot 24 at one side of the body. The slots 22 are closed at each end but the slot 24 is closed at its upper end only. The fact that the slot 24 is open at its lower end coupled with the fact that the ear extension 10 of the flange 11 are not rigidly connected, gives the parts 11 and 22 a certain flexibility. In consequence of that flexibility the frictional bond between the parts 11 and 22 in the assembled condition of the hair curler, may be amply strong to prevent accidental separation of the parts without risk of objectionable interference with the ready separation of the elements A and B when such separation is desirable. In the assembled condition of the hair curler, shown in Fig. 1, the lateral extensions 10 of the latter extend through the wide slot 24. The length of the cylinder 22 and its slot 24 is sufficient to permit the part 12 of the element A to turn out of its flame extinguishing position, into the position shown in Fig. 1 in which it permits the ignition of the fuel passing out of the wick tube 2. The slots 23 of the cylinder 22 permit the passage of air into the space surrounded by the flange 11 through the perforations in the latter, and also permit a relatively free movement of air into the space within the cylinder 22 and between the upper edge of the flange 11 and the flange portion 21 of the member B.

The body portion of the element B is a cylinder 30 having a closed lower end 31 and a longitudinal slot at one side which extends from the closed lower end of the cylinder to its open upper end. The internal diameter of the cylinder 30 is that required to snugly receive the cylindrical body 1 of the burner element A with the rib 4 of that element extending outwardly through the slot 32. Adjacent its upper end, the cylinder

body 30 is provided with a pair of lateral projecting ears 33 connected by a pivot 34 on which a lever or tong element 35 is pivoted. The upper end portion 36 of the lever 35 serves as a clamp holding the free ends of the hairs to be curled between it and the hair heating tube 20 in each hair curling operation. In cross section, the clamping portion 36 is a circular arc which in its normal position is coaxial with the heater tube 20. The lever end 36 is biased by a spring 37 for movement into a position in which it engages the hair heating tube 20 or the hair ends between the parts 20 and 36. The cylinder 30 and the lower end portion of the lever 35 form the handles of the curling iron or tongs and when pressed together move the lever part 35 and the heater tube 20 apart.

The precise dimensions of our improved curling iron are not critical. However our curling iron is characterized by the fact that it is adapted to be made in small sizes. In practice, it may well have an overall length a little less than 5 inches and its heater tube 20 may well be about 1 1/4 inches long, with an outside diameter of about $7/16$ of an inch. As will be apparent, the elements A, B and C may be readily separated for inspection, cleaning and repair purposes, or to facilitate the packaging or storage of the device and to permit the use of the element A as a cigarette lighter.

In the normal operative condition of the curler shown in Fig. 1, the lever element 35 has its clamping portion 36 connected to the portion of the lever along side of the enlarged tubular part 22 of the element B by a transverse portion 38 above said tubular portion and in position to prevent separation of any of the elements A, B and C so long as the lever remains in the position to which it is biased.

The invention may take various forms. Thus for example, the lever 35 may be pivotally mounted on the enlarged lower portion of the element B, thus permitting the element C to be eliminated. Alternatively, the construction illustrated can be simplified and its production cost reduced, as shown in Fig. 7 by replacing the element C by the element CA in which the cylinder 30 of Figs. 1 and 3 is replaced by the part 30A. The part 30A differs from the part 30 essentially only in that it omits all the part 30 except a short upper end portion to which the ears 33 are attached. With the element C in the form shown in Fig. 7, its length is appreciably reduced and less storage space is required to hold the disassembled curling iron parts. The part CA is also adapted for use with little or no change in association with cigarette lighters quite different in form from the lighter shown herein. As will be apparent, the cigarette lighter A of the structure can be separated from the other elements of the curler and used for its customary tobacco igniting purposes whenever desirable.

For convenience of description, we have hereinbefore referred to the hair curler as it appears in its erect position shown in Fig. 1. In normal use, however, the curler is customarily held in various positions including a horizontal and inclined positions, and sometimes it may be directly inverted for brief operating periods.

While in accordance with the provisions of the statutes, we have illustrated and described the best forms of embodiment of our invention now known to us, it will be apparent to those skilled in the art that changes may be made in

the forms of the apparatus disclosed without departing from the spirit of our invention as set forth in the appended claims, and that in some cases certain features of our invention may be used to advantage without a corresponding use of other features.

Having now described our invention, what we claim as new and desire to secure by Letters Patent, is:

1. In a curling iron, a hair heating structure comprising in combination, an open ended heating tube, a cigarette lighter including a body portion at one end of and detachably connected to said heating tube and enclosing a fuel and wick chamber, and having a wick tube for the extension therethrough from said chamber of a wick with the protruding end of the wick in position relative to said one end of said heating tube to maintain a flame between said wick tube and heating tube, and to pass combustion gases thereby formed into said one end of said heating tube, a wick closure element movable into and out of a closure position in which it substantially prevents the wick from withdrawing fuel from said chamber, said heating tube being formed to accommodate movement of said closure element into and out of said position, and enclosing a flint channel with an open end and an ignition wheel mounted for rotation on said body with the peripheral edge of said wheel in position to engage a flint protruding from said channel through the open end of the latter, a clamping element, and means connecting said element to said structure for movement relative to said tube into and out of a position in which it is adapted to clamp end portions of hairs curled about said heating tube against the latter.

2. A curling iron as specified in claim 1, in which a wire coil of good heating conducting metal is mounted in, and is spring pressed against the inner wall of said heating tube, and is operative to act as a transfer element to transfer heat from the combustion gases flowing through the heating tube to the latter.

3. A curling iron as specified in claim 1, in which said body portion and heating tube are telescopically connected to one another, and in which said structure comprises a casing open at its upper end and receiving a part of said body portion and in which said clamping member is pivotally connected to said casing and is spring biased for movement of a clamping portion into engagement with said tube and its offset relative to its handle portion and is connected to the latter by a transversely extending portion which interlocks with the enlarged lower end portion of said tube to prevent the separation of said lighter from said heating tube while the latter is engaged by said clamping portion.

4. A curling iron, comprising in combination a cigarette lighter type heating element having a body portion formed with a fuel and wick chamber, and a wick tube at one end of said chamber, a flint channel with a flint outlet adjacent said wick tube, an ignition wheel rotatably mounted on said body with its edge in position to engage a flint extending through said outlet, hair heating means detachably connected to said body portion and comprising an open ended heating tube with an enlarged perforated tubular extension at one end forming a previous wall for a combustion chamber into which said wick tube extends, a wick closure element movable into and out of a closure position in which it substantially prevents the wick from withdrawing fuel from said chamber, said heating tube being formed to accommodate movement of said closure element into and out of said position, a clamping element and means connecting said elements for movement of said clamping element into and out of position for clamping hairs against said heating tube.

5. A curling iron comprising in combination a cigarette lighter type heating element having a body portion formed with a fuel and wick chamber and with a wick tube at one end thereof, a longitudinal rib extending radially away from said said body and terminating at its free edge in a flint tube and an ignition wheel rotatably mounted on said body in proximity to said flint tube, and hair heating means detachably connected to said body portion and comprising an open ended tube with an enlarged perforated tubular extension at one end forming a wall of a combustion chamber into which said wick tube extends, a cylinder snugly receiving said portion and formed with a slot through which said rib extends and a clamping element pivotally connected to said cylinder and movable into and out of position for clamping hairs against said tube.
